UNITED STATES PATENT OFFICE.

GEORGE R. WADSWORTH, OF CLEVELAND, OHIO, ASSIGNOR TO THE PEERLESS MOTOR CAR COMPANY, OF CLEVELAND, OHIO, A CORPORATION OF OHIO.

DESIGN FOR AN AUTOMOBILE BODY AND HOOD.

44,647.

Specification for Design.

Patented Sept. 9, 1913.

Application filed November 1, 1912. Serial No. 729,157. Term of patent 7 years.

To all whom it may concern:

Be it known that I, GEORGE R. WADSWORTH, a citizen of the United States, residing in Cleveland, in the county of Cuyahoga and State of Ohio, have invented a new, original, and ornamental Design for an Automobile Body and Hood, of which the following is a specification, reference being had to the accompanying drawing, forming a part thereof.

The single figure of the drawing shows a side view of an automobile body and hood embodying my new design.

I claim:

The ornamental design for an automobile body and hood as shown.

GEORGE R. WADSWORTH.

Witnesses:

A. J. HUDSON,
N. C. HUBBARD.
